UNITED STATES PATENT OFFICE.

EGGBERT H. GOLD, OF CHICAGO, ILLINOIS.

CAR-HEATER.

SPECIFICATION forming part of Letters Patent No. 503,514, dated November 14, 1893.

Application filed September 30, 1892. Serial No. 447,413. (No model.)

To all whom it may concern:

Be it known that I, EGGBERT H. GOLD, a citizen of the United States, residing at Chicago, in the county of Cook and State of Illinois, have invented certain new and useful Improvements in Car-Heaters, of which the following is a specification, reference being had to the accompanying drawings.

My invention relates to car heaters of the class wherein a body of water or other heat absorbing substance is employed whereby a certain amount of heat is absorbed when steam is turned on, to be gradually given out after the steam is shut off. Radiators of this description have heretofore been devised in which a sealed tube filled with water or other heat absorbing substance has been placed within a larger tube which constituted the steam radiating surface. But with such sealed tubes difficulties occur in that the sealing is liable to be imperfect and if the contents are lost, there is no convenient way of replacing them. Care must also be taken to fill the tubes to precisely the desired point as over filling is liable to lead to their bursting in case they are exposed to such cold as to freeze the contents, while partial filling detracts from their efficiency.

My invention is designed to obviate these objections as well as to secure certain other advantages as will hereinafter appear.

In the accompanying drawings: Figure 1 is a longitudinal view partly in section of a radiator embodying my invention. Figs. 2, 3 and 4 are sections on lines 2 2, 3 3, and 4 4 respectively of Fig. 1. Fig. 5 is a longitudinal section of a portion of a tubular heater showing a modified form of the invention. Fig. 6 is a cross section also showing said modified form.

A is the outer shell or tube which is connected by the pipe B to the source of steam supply, the connection being either direct, or through a heater or radiator similar to that illustrated, if a series of such heaters or radiators are used. In like manner the pipe C forms a return to the steam generator or a connection to the neighboring radiator. Within the tube A is a smaller tube D which is made water tight by a suitable head E, one being at each end of the tube. At the middle of the tube D and near the top one or more

slots F are cut which permits the steam to enter the interior water tube D. The tube D bears for a portion of its distance against the outer tube A so that it is exposed to the cooling influence of the outer air to a limited extent. As shown in the drawings this circumferential contact is obtained by placing the tube D eccentric within the tube A so that the two are in contact at their tops. Any other mode of securing a partial circumferential contact between the two tubes, however, would serve the same end.

The heaters or radiators herein shown and described are very frequently used in cars or other moving vehicles and to prevent the surging of the water which gathers in the tube D up to the level of the slots F, I in some cases, provide transverse partitions G G, &c., as shown in Figs. 5 and 6, said partitions extending up to or near the top of the tube and having small openings g at their bottom through which the water can pass slowly so as to maintain the same level throughout the tube. Said openings, however, are too small to allow the sudden passage of any considerable quantity of water; hence, there will be no considerable agitation or overflow of the water contained in the tube D, if the latter is subjected to shocks such as arise from the rapid motion of the car or its sudden starting and stopping.

In practice the heater is erected without placing any liquid within the tube D. The steam used for heating is saturated so that the slightest lowering of the temperature results in the condensation of a portion thereof. Such of the steam as enters the tube D being exposed to the cooling influence on one side, will condense, but not with the same rapidity as the steam in the surrounding tube A. The water from condensation from the outer tube is drained away in the usual manner, however, while that in the inner tube D gradually accumulates until the level of the openings F is reached. Thus there will always be a constant supply of heat-absorbing liquid contained within the tube D.

I am aware that prior to my invention a steam radiator has been provided with longitudinal shelves or pockets arranged at the side thereof for the purpose of catching and holding water of condensation, but such ra-

diator is designed for stationary use such as in house heating and is not adapted for use as a car heater.

I am not aware, however, of any prior heater in which there is a perforated inner tube of substantially less diameter than the outer tube so that the space between said tubes constitutes a steam chamber, which leaves practically all of the surface of the exterior tube as a radiating surface with which the steam comes in direct contact; and by the term "substantially less diameter" I mean approximately such a difference as that shown in the drawings where sufficient room is left to constitute a steam chamber between the inner and outer tubes.

I claim—

1. In a car heater the combination of an outer tube connected with a steam supply and an inner tube of substantially less cross section than the outer tube, whereby the space between said tubes constitutes a steam chamber, said inner tube having closed ends and being provided with openings at or near its top, substantially as and for the purpose set forth.
2. In a car heater, the combination of an

outer tube connected with a steam supply, an inner tube of substantially less cross section than the outer tube whereby a space between said tubes constitutes a steam chamber, said inner tube being provided with closed ends and openings at or near its top, and transverse partitions within said inner tube, substantially as and for the purpose set forth. 30

3. In a car heater the combination, of an outer tube connected with a steam supply and an inner tube having closed ends and openings at or near its top, said inner tube being in contact with the outer tube at one point only of its periphery, substantially as and for the purpose set forth. 35

4. In a car heater, the combination of an outer tube connected with a steam supply, an inner tube provided with closed ends, and openings at or near its top, said inner tube being in contact with the outer tube at one part only of its periphery, and transverse partitions within said inner tube, substantially as and for the purpose set forth. 40
